UNITED STATES PATENT OFFICE

THEODORE E. CAYER, OF TAUNTON, MASSACHUSETTS, ASSIGNOR TO REED & BARTON,
OF TAUNTON, MASSACHUSETTS, A CORPORATION OF MASSACHUSETTS

DESIGN FOR A SPOON OR SIMILAR ARTICLE

Application filed December 15, 1931. Serial No. 42,088. Term of patent 7 years.

To all whom it may concern:

Be it known that I, THEODORE E. CAYER, a citizen of the United States, residing at Taunton, in the county of Bristol and State of Massachusetts, have invented a new, original, and ornamental Design for a Spoon or Similar Article, of which the following is a specification, reference being had to the accompanying drawings, forming a part hereof.

Fig. 1 is a plan view of a spoon showing my new design;

Fig. 2 is a reverse plan view of the same; and

Fig. 3 is an enlarged cross section on line 3-3 of Fig. 1.

I claim:

The ornamental design for a spoon or similar article as shown.

THEODORE E. CAYER.
